(57) **CLAIM**

We claim the ornamental design for a vehicle front window vent visor, as shown and described.

DESCRIPTION

FIG. 1 is a perspective view of the vehicle front window vent visor as viewed from the exterior of the design.

FIG. 2 is a perspective view of the design shown in FIG. 1 as viewed from the interior of the design.

FIG. 3 is a front elevational view thereof.

FIG. 4 is a rear elevational view thereof.

FIG. 5 is a top plan view thereof.

FIG. 6 is a bottom plan view thereof.

FIG. 7 is an end elevational view as taken from the right of FIG. 3.

FIG. 8 is an end elevational view as taken from the left of FIG. 3; and,

FIG. 9 is an enlarged sectional view taken through line 9—9 of FIG. 4.
